UNITED STATES PATENT OFFICE.

GEORGE W. STRONG AND GEORGE UHLIN, OF ROSEDALE, KANSAS.

GRAIN-CAR DOOR.

Application filed July 7, 1925. Serial No. 42,030.

To all whom it may concern:

Be it known that we, GEORGE W. STRONG and GEORGE UHLIN, citizens of the United States, residents of Rosedale, in the county 5 of Wyandotte and State of Kansas, have invented certain new and useful Improvements in Grain-Car Doors; and we do hereby declare the following to be a full, clear, and exact description of the invention, such as 10 will enable others skilled in the art to which it appertains to make and use the same.

Our present invention has for its object the provision of a grain door for cars which will effectually withstand the pressure of 15 the grain, may be easily manipulated from the outside of the car to permit discharge or unloading of the grain, and will be held effectually in its raised position. The present invention seeks particularly to reduce the 20 number of parts and simplify the construction without impairing the efficiency of the device. These stated objects and other objects which will incidentally hereinafter appear are attained in such an apparatus as 25 is illustrated in the accompanying drawings, and the invention resides in certain novel features which will be particularly pointed out in the appended claims.

In the drawings, Figure 1 is an elevation 30 of our improved door viewed from the inside of the car, the door being closed;

Figure 2 is a similar view of the outer side of the door;

Figure 3 is a vertical transverse section 35 showing the door lowered in full lines and raised in dotted lines;

Figure 4 is a detail horizontal section on the line 4—4 of Fig. 3;

Figure 5 is a detail perspective of the 40 upper end of the guide facing or shoe on the door.

The car body may be of any approved construction having a door opening in its side defined by door posts or jambs 1 rising from 45 the sills or floor beams 2. On their inner sides, the jambs 1 are faced with metal strips 3 which extend nearly the full height of the jambs, and in the opposed sides of the jambs recesses 4 are formed along the corners thereof, the upper ends of the recesses being offset outwardly, as at 5, and the edges of the facing strips projecting over the recesses so 50 that vertical grooves or guideways are produced. In the inner sides of the jambs, adjacent the upper ends of the same, are recesses or sockets 6 and the upper extremities

of the facing strips 3 are disposed at said sockets or recesses to reinforce the edges of the same and prevent chipping of the edges.

The door 7 may be a single board or metal 60 plate or a plurality of boards or plates but it should be of such length as to completely span the door opening and have its ends rest against the inner sides of the door jambs so that the outward pressure of the grain 65 will be positively and effectually resisted. Secured to the outer side of the door, at the ends thereof, are facing strips or shoes 8 which bear upon the facing strips 3 and are provided with flanges 9 which project into 70 the door opening and slidably engage the respectively adjacent jambs. The endwise movement of the door, under the friction of the grain and the sudden starting and stopping of the car, is thus prevented and it is 75 held to a rectilinear path in raising and lowering. At the upper end of each flange 9 is a lateral trunnion 10 engaging in the groove or recess 4 of the adjacent jamb and adapted to slide therein and pivotally sustain the door and also seat in the offset 5 when the door is fully raised. The upper extremity of the facing strip or shoe 8 is slit longitudinally and its central portion is bent inwardly to form a tongue 11 extending across the upper edge of the door, and an upstanding tongue 12 which is adapted to engage in the recess or socket 6 when the door is raised and swung up close to the car roof, it being noted at this point 80 that the socket 6 and the offset 5 are approximately in the same horizontal plane. The tongues 11 project somewhat inwardly beyond the door and have openings 13 through their ends for a purpose which will 85 presently appear.

On each shoe 8, at the edge of the door, is a lug 14 to which is attached the lower end of a chain or cable 15 which has its upper end attached to and adapted to wind 100 on a shaft 16 which is rotatably supported within the car above the door opening. On one end of the shaft is a worm gear 17 meshing with a worm 18 on a shaft 19 which extends through the side of the car body and is equipped with a handle 20 outside of the body.

A supplemental door section or panel 21 is provided above the door 7 and this panel 110 has hinge straps or brackets 22 secured upon its inner side, said straps terminating at their lower ends in curved hooks 23 em-

gaged through the openings 13 in the tongues 11 whereby the panel or secondary door section will be hingedly secured to the main door 7. The panel or secondary section may 5 thus be disposed above and in the same vertical plane with the main door section or may be swung down at the inner side of the latter. To retain the panel in its raised position, hooks 24 are pivoted upon the door 10 jambs in position to engage over the top edge of the panel, as will be understood.

The flanges 9 are provided with openings 25 therethrough at intermediate points of their height which, when the door is 15 lowered, register with keeper sockets 26 in the jambs, and bolts 27 are mounted upon the outer side of the door with their outer ends resting in the openings 25 in position to engage the sockets 26. A lever or handle 20 28 is mounted on the door and operatively connected through any approved means with the inner ends of the bolts so that rocking the lever will project or retract the bolts.

25 When the grain is to be unloaded, the bolts are retracted and the shaft 16 is caused to rotate so as to partly wind the cable 15 thereon to raise the door from the door sill, permitting the grain to flow under the door into a receptacle provided therefor. As the volume of grain against the door diminishes, the secondary panel will swing down, (the hooks 24 having been released) and the winding of the cables is continued 30 until the door is fully raised. The cables are connected to the door at points below the top thereof and at the inner side of the same so that they tend to swing the door about the trunnions as well as to raise it. 35 As the door approaches the car roof, it will swing inwardly and eventually will assume a substantially horizontal position close to the roof, the trunnions 10 moving into the offset seats 5 and the tongues 12 40 entering the sockets 6 to cooperate with the cables and the worm gearing in holding the door in its extreme upper position. In this extreme upper position, the door will obviously be out of the way and workmen may 45 pass freely into the car to shovel out the grain located at points therein remote from the door opening.

Our improved door is simple in construction, is easily manipulated, and is highly 55 efficient in retaining the grain within the car. It is to be particularly noted that the shoes on the door cooperate with the facing strips on the jambs to overcome wear between the door and the jambs, also serve as 60 guides and stops to properly position the door over the door opening and prevent end-

wise movement of the door across the opening, aid in supporting the door in its fully raised position, and also provide part of the means for suspending the door and for connecting the secondary door section or panel thereto.

Having fully described our invention what we claim as new and desire to secure by Letters-Patent, is:—

1. The combination of door jambs having ways on their opposed sides and recesses in their inner sides adjacent the upper ends of the ways, a door, shoes secured on the outer side of the door to ride on the jambs and provided at their upper ends with trunnions engaging in said ways and with tongues adapted to engage in said recesses, and means for raising and lowering the door.

2. The combination of door jambs, a door spanning and bearing against the jambs, shoes secured upon the outer side of the door to ride on the jambs, tongues projecting inwardly from the upper ends of the shoes across the top of the door, a secondary door section hinged to said tongues, means for releasably holding said secondary section in upright position above the door, and means for raising and lowering the door.

3. The combination of door jambs, a door spanning and bearing against the jambs, shoes secured upon the outer side of the door to ride upon the jambs, flanges along the opposed edges of the shoes to slidably engage the opposed sides of the jambs, lugs upon the shoes at the end edges of the door, a winding shaft above the door, and flexible connections between said shaft and said lugs.

4. The combination of door jambs having recesses extending along their opposed sides at their inner corners; said recesses having outwardly projecting offsets at their upper ends and the jambs having sockets in their inner sides adjacent said offsets, facing strips on the inner sides of the jambs extending to said sockets and projecting over the recesses, a door spanning the jambs, means for raising and lowering the door, and shoes secured to the outer side of the door and having flanges slidably engaging the opposed sides of the jambs, said flanges having trunnions at their upper ends riding in the recesses in the jambs and adapted to engage the offsets at the upper ends of the recesses, and the shoes being provided at their ends with upstanding tongues to seat in the sockets in the jambs.

In testimony whereof, we have signed this specification.

GEORGE W. STRONG.
GEORGE UHLIN.
